UNITED STATES PATENT OFFICE.

MAX ROSENKRANZ, OF PITTSBURGH, PENNSYLVANIA, ASSIGNOR TO NATIONAL TUBE COMPANY, OF PITTSBURGH, PENNSYLVANIA, A CORPORATION OF NEW JERSEY.

TROUGH-DUMPING MECHANISM.

1,399,882.

Specification of Letters Patent. Patented Dec. 13, 1921.

Application filed January 13, 1921. Serial No. 486,953.

To all whom it may concern:

Be it known that I, MAX ROSENKRANZ, a citizen of the United States, and resident of Pittsburgh, in the county of Allegheny and State of Pennsylvania, have invented 5 certain new and useful Improvements in Trough-Dumping Mechanisms, of which the following is a specification.

This invention relates to pipe cooling 10 tables, and more particularly to automatic lifts for the trough covers thereof, and has for one of its objects the provision of such a device that will be automatic in operation, yet simple in construction and composed of 15 few parts.

Heretofore, various methods have been devised for automatically operating the covers of dump troughs. Automatic circuit 20 make and break devices in combination with suitable magnetic lifts have been employed, but were unsuccessful due to the intense 25 heat and wear that a cover lift is necessarily subjected to.

Various fluid operated devices were tried 30 but were found wanting, and discarded.

At the time of this invention the practice had reverted back to the old and primitive method of operating the cover lift by 35 means of compressed air actuated levers controlled by hand valves.

The hand controlled compressed air 40 method is superior to the automatic means heretofore devised, since it is not liable to get out of order. However it had its faults 45 as do all methods depending on manual operation. The operator was compelled to be alert at all times and to operate the control valves several times in a single minute. If he delayed a fraction of a second it 50 causes a jam, and if he closes the cover a fraction of a second too soon he pinches a pipe under the cover and causes a jam. These jams compelled the mill to shut down 55 and caused a loss of much valuable material 45 and time.

The present apparatus is automatic and certain in operation, and does not depend 60 in any manner upon a human agency for operation or control and, therefore, has none 50 of the objectionable features of the previous methods.

Various other objects and advantages will 65 be brought out in the following specifica-

tion and claims, and illustrated in the accompanying drawings, in which—

Figure 1 is a plan showing a portion of a 55 pipe cooling table, having a dumping trough constructed in accordance with my invention.

Fig. 2 is a rear elevation of the construction of Fig. 1.

Fig. 3 is a sectional elevation on the line III—III of Fig. 1.

Fig. 4 is a sectional elevation on the line IV—IV of Fig. 1.

Fig. 5 is a detail sectional elevation showing the dump trough with the cover lifted to discharge a pipe.

Fig. 6 is a plan of a slightly modified embodiment of my invention.

Fig. 7 is a rear elevation of the construction of Fig. 6.

Referring to the drawings, like reference numerals designate like parts throughout the several views thereof. The dump trough 75 2 is supported upon a plurality of adjustable stands 3 secured in position to the rear of the cooling table 4 and in line with the sizing rolls 5 in the housings 5'. The table 4 is provided with conveyer members 4' and 80 5' may be of any well known construction, and will not be described further, since it is not a part of this invention.

The space between the trough 2 and table 4 is bridged by plates or skids 6 as is the usual practice.

Referring particularly to Figs. 1, 2, and 3, the numeral 7 designates the trough cover which is connected to the trough along its rear edge by a plurality of hinge members 90 8. Midway between its ends the cover is provided with an operating or lifting lever 9 which is fulcrumed in the forked bracket 10 secured to the trough. The lever 9 is connected by means of a link 11 to the 95 piston rod 12 of an air cylinder 13.

A rocker block 14 is adjustably mounted on the forward end of a counter weighted lever 16 which is pivotally mounted in the forked bracket 15 adjacent the end of the trough 100 farthest away from the rolls 5. The lever 16 has a sliding connection with the vertically movable valve stem plunger 17 of the compressed air inlet valve 18 which controls the flow of air to the air cylinder 13. 105 The valve 18 is a one-way valve and is con-

connected with a pipe 19 leading from a suitable source of air supply and is also connected with cylinder 13 by a pipe 20.

The rocker block 14 has a longitudinally 5 tapered recess 14^b in its under face and is adapted to be operated by the pipe when it passes along the trough. The pipe entering under the tapered recess 14^b will have a wedging action, raising the rocker and 10 forcing the plunger 17 down, opening the valve and allowing the air to flow into the cylinder 13, thus opening or raising the trough cover and releasing the pipe onto the table 4 when the rocker 14 will drop and 15 return the valve.

A second rocker block 21 is arranged adjacent the forward end or the roll end of the table to control the exhaust of the air from cylinder 13 and the lowering of the 20 cover 7.

The block 21 is identical with the block 14, has its bottom face provided with a recess 21^a, and is adjustably mounted on a counter-weighted lever 23 fulcrumed at 22, and having a sliding connection with the plunger 24 25 of an exhaust valve 25 connected by pipe 26 to the cylinder 13.

The valve 25 is just opposite to the valve 18 and is closed by the lifting of the 30 rocker 21.

Just as the hot pipe passes through the rolls 5 it will pass into the recess 21^a on the bottom of the rocker 21, raising it and closing the exhaust valve 25, and as the pipe 35 passes out from under the rocker 21, the rocker will drop of its own weight, lifting the plunger 24 and opening the exhaust valve 25.

The effect of operation of the rocker 21 is 40 that the trough cover 7 can not fall until after the pipe has passed clear of the rolls 5, and, therefore, the danger of jams is entirely eliminated.

The general operation is as follows—A 45 pipe in passing from the rolls 5 will operate the rocker 21 and close the exhaust valve 25. It will then continue along the trough 2 under the cover 7 until it passes under the rocker 14, when it will operate the inlet valve 18 50 and allow compressed air to flow into the cylinder 13, forcing down the piston rod 12 and raising the cover 7. The cover will not fall until after the pipe has passed from under the rocker 21 and permitted it to drop, thus 55 raising the plunger 24 and opening the exhaust valve 25.

In Figs. 4, 5, and 6 I have shown a slightly modified arrangement in which only the one rocker 14 is used, connected to a two-way 60 valve 26 to raise and lower the cover 7 instead of operating the one-way inlet valve 18 to only raise the cover. The valve 26 is 65 adapted to receive air through the pipe 19 and is connected with the cylinder 13 by the pipe 20, as is the valve 18. When the rocker

14 is lowered it opens the valve 26 to the atmosphere through the exhaust port 27, thus releasing the air pressure from the cylinder 13 and allowing the cover 7 to drop.

The operation of this last described construction is similar to that previously described, with the exception that the one rocker operates a single valve which controls both the inlet and outlet or exhaust of the cylinder 13.

While I have illustrated and described these two embodiments of my invention with great care as to details, it will be expressly understood that I do not wish to be limited to the specific construction set forth, since 80 various changes in design and combination of parts may be made by those skilled in the art, without departing from the spirit of my invention as defined in the appended claims.

I claim:—

1. The combination with the dumping trough of a pipe cooling table having a hinged cover, of a fluid actuated piston for operating said cover, a control valve for controlling the flow of fluid to said piston, a lever fulcrumed intermediate its ends on said dumping trough, and having one end connected to said valve, and a rocker block on the other end of said lever, said rocker block having a tapered recess therein adapted to receive the pipe passing under said cover, thereby rocking said lever and actuating said valve.

2. The combination with the dumping trough of a pipe cooling table having a hinged cover, of a fluid actuated piston and lever mechanism for operating said cover, a control valve mounted on said trough for controlling the flow of fluid to said piston, a lever fulcrumed intermediate its ends on said trough and having a sliding connection adjacent its one end with said valve, and a rocker block adjustably mounted on the other end of said lever, said rocker block having a 105 tapered recess in its under face adapted to receive the pipe passing under said cover, thereby rocking said lever and actuating said valve.

3. The combination with the dumping trough of a pipe cooling table having a hinged cover, of a fluid actuated piston for operating said cover, and a valve and lever mechanism adjacent each end of said trough adapted to be actuated by the pipe to be 115 cooled for controlling the flow of fluid to and from said piston.

4. The combination with the dumping trough of a pipe cooling table having a hinged cover, of a fluid actuated piston for operating said cover, an inlet control valve 125 adjacent one end of said trough, lever mechanism for operating said valve, an exhaust control valve adjacent the other end of said trough, and lever mechanism for operating said last named valve, said lever mechanism 130

being adapted to be automatically and independently operated by the pipe in its passage along said trough.

5. The combination with the dumping trough of a pipe cooling table having a hinged cover, of a fluid actuated piston for operating said cover, a valve adjacent one end of said trough for controlling the inlet of fluid to said piston, a second valve adjacent the other end of said trough for controlling the exhaust from said piston, a lever adjacent each end of said trough, said levers

being fulcrumed intermediate their ends in forked bearings on said trough and having one end slidably connected to said valves, 15 and a rocker block on the other end of each of said levers, said rocker blocks having a tapered recess therein adapted to receive the pipe passing under said cover, thereby rocking said levers and actuating said levers. 20

In testimony whereof, I have hereunto set my hand.

MAX ROSENKRANZ.
